UNITED STATES PATENT OFFICE.

WILLIAM A. BINGHAM, OF CLEVELAND, OHIO.

WINDOW LATCH.

Application filed April 19, 1924. Serial No. 707,590.

To all whom it may concern:

Be it known that I, WILLIAM A. BINGHAM, a citizen of the United States, residing at Cleveland, in the county of Cuyahoga, and State of Ohio, have invented a certain new and useful Improvement in a Window Latch, of which the following is a full, clear, and exact description, reference being had to the accompanying drawings.

10 This invention relates to a clasp for windows, and is particularly adapted to hold a lift or vertically swinging window in open horizontal position.

15 Various devices have been employed for this purpose, most of which I have found to be buttons, hooks or similar contrivances which require the use of both hands of the person opening the window. I have provided a latching means which will do away 20 with the necessity for raising the window with one hand and fastening it in position with the other.

Moreover I have provided a spring latch 25 capable of being very simply and cheaply constructed of a small number of parts and which lends itself readily to adaptation for this particular type of window.

An object is to so construct such a latch 30 that it may be very cheaply manufactured and yet be durable in service.

My invention is more fully set forth in the description which pertains to the accompanying drawing and its essential characteristics will be summarized in the claim:

35 In the drawings, Fig. 1 illustrates my latch attached to the ceiling above the window; Fig. 2 is a perspective showing one form of my latch; Fig. 3 is a perspective of a modified form.

40 In the drawings I have shown at A, Fig. 1, a window casing having a window B hinged at C, the open and latched position of the window being indicated by the dot and dash lines B¹. I have shown my latch 45 as attached to a joist member D in the ceiling of the room or basement as the case may be. My latch generally is indicated at 1 and is formed of an L-shaped bracket member 2, the upper end of which is bent at right angles as at 3 and perforated at

4, for attaching to the ceiling. In the form shown in Fig. 2, I have provided a movable latching portion 6 hinged at 7 to the plate 2 and having a reduced turned-in portion 8 adapted to slide freely through a hole 9 in the plate. A light spring 11 secured to the plate at 12 is adapted to enter a hole in the tongue 8 and hold the tongue forwardly in the position shown in Figs. 1 and 2.

In the modified form, I have retained the L-shaped member 2 substantially as shown in Fig. 2, but have provided a rigid latching 6^a in place of the movable member 6. The tongue 8^a being shown as riveted or bent over close to the hole 9. This form is better adapted to a window that is a greater distance from the ceiling and in which the frame of the member 2 will serve the purpose of a leaf spring in latching the window in its raised position. This form might be also made in the same proportions as that shown in Fig. 2 but of lighter and therefore more resilient metal.

The latch fastened to the ceiling at such a distance from the hinge of the window that the lower sash bar of the window will swing against the inclined portion of the latch 6 pushing it inwardly and thereafter resting upon the tongue 8. To release the latch, it is simply necessary to press the members 2 and 6 together with the thumb and fore finger of the hand, while steadyng the window against an abrupt fall with the free fingers of the same hand. Thus I have provided a latch which may be quickly and easily operated to latch the window in raised position while it may be as simply released.

I may provide other means for releasing the latch, such as by attaching a cord to the end of the projection 8 extending rearwardly of the bar 2 in the form shown in Fig. 2 and by this means the window might be released from a remote part of the room. To the modification shown in Fig. 3 I would attach such a cord to the curled lower end of the member 6^a.

Owing to the fact that most windows of this type are found in proximity to a floor or ceiling construction such as shown, it

will be seen that my latch provides a very simple and efficient fastening and releasing means therefor.

I claim:

- 5 A lift window latch comprising a depending bar, a latch member having its lower end portion loosely hooked into the bar and having an inclined intermediate portion and

having at its upper end a tongue extending through the opening in the bar, said tongue having an opening through it beyond the bar, and a leaf spring secured to the bar and extending through the opening in the tongue. 10

In testimony whereof, I hereunto affix my signature.

WILLIAM A. BINGHAM.
